CONDENSER

Henry E. Byer, Rosebank, N. Y.

Application May 3, 1934, Serial No. 723,642

3 Claims. (Cl. 261—108)

This invention relates to improvements in condensers and more particularly to the type of counter-current condenser for the condensation of steam as described in my prior Patent No. 1,929,403, patented October 10, 1933.

In my prior patent I have disclosed an improved apparatus for the condensation of steam and other condensable gases by the counter-current transfer of the gases through certain balanced water curtains formed by weirs and deflector plates. I have now made a further improvement in such a type of condenser which simplifies the internal construction and renders the condenser more efficient in use.

It is one of the principal objects of my invention to produce a jet type of condenser with a balancer curtain of water flowing through the condensing chamber, such curtain being provided with openings on opposite sides which permit the steam to contact on both sides of the water curtain and not deflect or interrupt the continuous sheet effect.

Another object of my invention is to provide a condensing chamber of a counter-current condenser with a conical form of water curtain having a closed top and with gaps in the side into which the steam may enter, the water flow being such that the steam must pass through at least two sheets of water before reaching the air chamber.

A further object of my invention is to provide a single weir and substantially circular water deflector mounted on a transverse cross piece which forms a substantially continuous sheet of water for the effective condensation of condensable gases and which makes the apparatus more simple in construction and more effective in use.

Further objects and advantages of my invention will appear from the following disclosure thereof taken in connection with the attached drawing which illustrates a preferred form of embodiment thereof and in which:

Figure 1 is a vertical section through an improved form of jet condenser.

Figure 2 is a horizontal section taken substantially on the line 2—2 of Figure 1 and looking downward, and

Figure 3 is a horizontal section on the line 3—3 of Figure 1 and diagrammatically illustrating the flow of water.

The improved type of condenser 10 shown in Figure 1 is provided with a condensing chamber 12 into which the steam or other condensable gases enter through the conduit 14. A water chamber 16 is formed above the condensing

chamber 12 by the weir 18 into which the water flows from the conduit 20. An air collection chamber 22 for uncondensable gas is also provided at the top of the condenser 10 from which the gases are removed by a suitable vacuum pump or other means through the conduit 24. If desired, a baffle plate 25 may be provided below the opening to prevent splashing or escape of water. The hot water is discharged from the bottom of the condenser 10 through the conduit 26 which may be provided with a suitable length of pipe for a barometric leg.

The weir 18 is adapted to retain a substantial quantity of water which when it overflows, will pass downward in a substantially cylindrical sheet 15 onto the umbrella shaped baffle 28 and thence to deflecting ring 30 by which it is deflected inwardly and past the steam opening 14. The deflecting ring 30 causes the water to fall in the form of a hollow cone or sheet 32 and the curtain 20 has two diametrically opposite gaps, more particularly as shown in Figure 3, due to the transverse baffle support 29.

As shown in Figure 2, the baffle support 29 which is preferably V shaped with the narrow point on top for the least interference with water flow, extends substantially entirely across the condenser and projects beyond the edges of the baffle 28. This interrupts the water flow at the desired points 34 so that the steam and uncondensable gases may enter. The steam also passes around the outside of the water curtain as generally indicated at 32 and the curtain will continue as a continuous sheet as the gas pressure is balanced on both the inside and the outside. This affords an extremely large water contacting surface to condense the steam, and it will not be blown aside by steam pressure.

The steam and other uncondensable gases which enter the condensing chamber 12 come in contact with the water sheet 32 and then tend to rise through the water sheet 33 consisting of the water passing off the edge of the baffle 28. The balance of the uncondensed steam and the uncondensable gases then enter the secondary condensing chamber 13 and pass upward through the water sheet 34 which flows from the top of the weir 18. In normal operation all of the steam will be condensed by this time and the uncondensable gases which rise to the air collecting chamber 22 will be drawn out through the discharge conduit 24.

In this type of construction the water flowing through the condenser flows evenly and without any pulsating effect. This eliminates the pulsat-

- ing operation in the condenser and totally eliminates any pulsating effect in the total volume of steam exposed to vacuum. I am therefore able to eliminate entrainment losses which are normally present in condensers having a series of flat plates or baffles. Such a condenser is also less expensive to manufacture in that it has fewer parts than in the prior known structures and it has no material maintenance problems.
- 10 While I have shown a preferred form of embodiment of my condenser it will be understood that modifications may be made therein and I therefore desire a broad interpretation of my invention within the scope and spirit of the description thereof and of the claims appended hereinafter.
- 15 I claim:
1. A counter-current vapor condenser of the class described comprising a primary condensing chamber having an inlet for vapors, a secondary condenser chamber, a water receiving chamber and an uncondensable vapor collecting chamber, a weir in said water receiving chamber to form a closed curtain of water between the uncondensable vapor collecting chamber and the secondary condensing chamber, an umbrella shaped baffle below said closed curtain of water to deflect the curtain of water against the sides of the condenser to close the secondary condensing chamber, a deflector portion on said condenser below the secondary condensing chamber to form a second curtain of water flowing through the primary condensing chamber and being spaced from the sides thereof, a transverse member in alignment with the vapor inlet in the path of flow of the second curtain of water to form openings on opposite sides of the curtain of water whereby vapors may enter within the curtain of water without any substantial

deflection of the water curtain, and means to discharge uncondensed vapors and water at opposite ends of the condenser.

2. A steam condenser of the class described having a condensing chamber having an inlet into which steam is admitted, a water chamber above the condensing chamber, a weir in said water chamber and an umbrella shaped deflector below said weir, said deflector and weir forming a closed curtain of water separating the condensing chamber from the water chamber, deflector means near the top of the condenser chamber to form a substantially conical curtain of water in the condensing chamber, and means to interrupt the water flow from said deflector to form openings in said water curtain adjacent the steam entrance whereby the entering steam will pass into and around the water curtain and the curtain will remain in pressure balance.

3. A steam condenser having a main steam condensing chamber with a steam inlet therein, a secondary steam condensing chamber, and an air collection chamber, said air collection chamber having a water inlet and an air outlet, means to form a closed curtain of water between said air collection chamber and said secondary steam condensing chamber, means to form a second closed curtain of water separating said secondary steam condensing chamber from said main condensing chamber, means to form a conical flow of water through said main condensing chamber, and means to form diametrically opposite openings in said conical flow of water in alignment with said steam inlet whereby steam may surround said water flow without substantially deflecting it.
